Patented Mar. 28, 1922.

UNITED STATES PATENT OFFICE.

WILLIAM C. DILLON, OF FORT DODGE, IOWA.

AUXILIARY LOCK FOR VAULT LOCK MECHANISM.

1,410,800.

Specification of Letters Patent. Patented Mar. 28, 1922.

Application filed February 10, 1920. Serial No. 357,659.

To all whom it may concern:

Be it known that I, WILLIAM C. DILLON, a citizen of the United States, residing at Fort Dodge, in the county of Webster and State of Iowa, have invented certain new and useful Improvements in Auxiliary Locks for Vault Lock Mechanism, of which the following is a specification.

This invention relates to safe and vault locks, and the primary object of the invention is to provide a device for engaging a vault or safe lock bolt mechanism, when the combination lock has been forced inwardly, so as to prevent the operation of the bolts and opening of the door.

The most common methods employed by burglars of safes and vaults are to blow the combination lock inwardly by explosives, or to punch the lock in by knocking off the knob and driving in the spindle, or by pulling out the pin which is attached to the knob and punching off the lock, or by drilling a hole through the door and punching off the lock. Any one of the above methods permits the sliding of the bolt mechanism, and another object of the invention is to provide an improved means for effectively preventing the sliding back of the locking means if any one of these methods are employed.

A further object of the invention is to provide an improved device embodying a block adapted to be moved into the path of the bolt mechanism, when the combination lock has been tampered with by unauthorized persons, thereby absolutely holding the bolt lock mechanism in operative position against movement.

A further object of the invention is to provide an improved means for operating the block so as to move the same into the path of the bolt lock mechanism when the combination lock has been forced.

A further object of the invention is to provide means for preventing the severing of the connection between the block and combination lock by the boring of a hole in the safe door adjacent to the combination lock and cutting and filing the connection, thereby making the device positively burglar-proof.

A still further object of the invention is to provide an improved auxiliary locking device for the bolt lock mechanism of a vault or safe door, when the combination lock has been rendered inoperative, of the above character which is durable and efficient in

use, one that is simple and easy to manufacture, and one which can be placed upon the market at a reasonable cost.

Other objects of the invention will appear in the following detailed description taken in connection with the drawings, forming a part of this specification, in which drawings:

Figure 1 is a fragmentary rear elevation of a vault door and frame, showing the improved auxiliary locking device applied thereto.

Figure 2 is a fragmentary enlarged end elevation of the improved device showing the same in applied position, and

Figure 3 is an elevation of the improved device showing the same applied to a vault door.

Referring to the drawings in detail, wherein similar reference characters designate corresponding parts throughout the several views, the letter A indicates the improved auxiliary locking device for the vault door B, having the bolt lock mechanism C which is adapted to engage the door frame D, and the combination lock E.

The door B, the frame D, the vault lock mechanism C, and the combination lock E is one of the ordinary or any preferred construction and the vault door B includes the body 5 having the usual inwardly extending flange 6 which is arranged adjacent to and parallel with the usual flange 7 carried by the door frame D.

The bolt lock mechanism C includes the usual bolts 8 connected by the vertically extending bar 9 by suitable bolts 10 or other fastening elements. The bar 9 is provided with the inwardly extending arm 11, which is disposed in the path of the combination lock mechanism E which prevents the sliding thereof when the combination has been set.

The improved relocking device A for the bolt mechanism C includes a rod 12 which is adapted to be inserted through a suitable opening formed in the flange 6. The opening in the flange 6 may be drilled at any desired place, so that the rod 12 can be placed at different points on different safes or vaults and thereby render the finding of the same by a burglar impossible. The terminals of the rod 12 are threaded as at 13 and 14 and the threaded end 13 is adapted to be inserted through the opening formed in the flange or ledge 6 and the same is held

in place by suitable lock nuts 15 and 16, which are threaded on the threaded end 13 of the bolt into frictional engagement with the opposite faces of the flange 6. The rod 12 extends inwardly from the flange 6 directly in rear of the connecting bar 9 of the bolts and the threaded terminal 14 thereof projects beyond the inner edge of the connecting bar 9. The threaded terminal 14 has mounted thereon the solid block 17, which has one face thereof flattened as at 18, and when the face 18 is arranged in parallel relation to the bar 9, which is the normal position thereof, the free sliding movement of the bar 9 is permitted, but when the block is turned on the rod 12 so that the face 18 lies at an angle to the bar 9, the block extends in the path of the bar 9, and prevents movement thereof. To hold the block 17 on the threaded end 14 against accidental movement, a lock nut 19 is provided for frictionally engaging the inner surface thereof, and if so desired, a suitable lock washer 20 may be employed and arranged between the lock nut 19 and the block 17 for holding the same against accidental rotation. The block 17 is provided with an opening 21 adjacent to the periphery thereof, and the opening is directly on the opposite side of the rod 12 from the flat face 18. A flexible wire or cord connector 22 has its upper terminal inserted in the opening 21 and knotted as at 23. The connector 22 is then brought downwardly and secured to the combination lock mechanism B or anchored in such a manner to the door that the block will be rotated against the tension of the spring washer, when the combination lock has been destroyed. The rotation of the block 17 will move the flattened face 18 thereof at an angle to the bar 9 and thereby bring the block into the path of the bar 9 and prevent movement of said bar.

As clearly shown in Figure 1 of the drawings, the method of anchoring the lower end of the connector 22 to the door B consists of extending the connector 22 across the combination lock E and securing the same to an eye 25 arranged directly below and adjacent to the rear end of the combination lock mechanism E. Thus it will be seen that when the combination lock is moved inwardly the wire will be pulled, which will rotate the block 17.

To prevent the severing of the connection 22 by a burglar boring a hole adjacent to the combination lock and inserting a tool therein and cutting or filing the connector, a cylindrical protector 24 is rotatably mounted on the connector 22, between the rod 12 and the combination lock E. If a tool is placed against the protector, the same will rotate and thereby prevent the cutting or filing of the connector. After the combination lock has been destroyed and

the block 17 rotated, the force of the blowing in of the lock will break the connector and the protector 24 will slide off of the same. Owing to the fact that the connector 22 is flexible or bendable, it is impossible for a burglar to push up on the connector to turn the block after the combination lock has been blown off. The position of the rod 12 and the block 17 is made known to the owner of the safe or vault by exact measurements, and in case the block 17 has been operated by burglars trying to open the safe, the owner of the safe or vault can have a hole drilled in the front side of the door at a point at right angles to the center of the flat side 18 of the block 17, and a blunt tool can then be inserted through the hole in the door and pushed against the peripheral notches 26 until the block 17 has been turned a sufficient distance to position the face 18 in parallel relation with the attaching bar 9. To facilitate the returning of the block 17 to its normal position, an inwardly extending opening 27 is formed in the periphery of the block 17 directly in rear of the face 18 and when the opening 27 comes into alignment with the holes drilled for insertion of the tool, the operator can then tell that the face 18 is in parallel relation to the bar 9.

From the foregoing description, it can be seen that an improved locking means is provided for the vault locking mechanism of a vault or safe door which will absolutely prevent movement of the bolt lock mechanism when the combination lock has been destroyed.

Changes in details may be made without departing from the spirit or scope of my invention; but,

I claim:

1. As a new article of manufacture, an auxiliary locking device for the bolt mechanism of vault doors comprising a threaded rod, a pair of door engaging nuts threaded on one end of said rod, a block threaded on the other end of said rod, a nut threaded on said rod adjacent to said block, and a lock washer interposed between said last mentioned nut and the block.

2. As a new article of manufacture, an auxiliary locking device for the bolt mechanism of vault doors comprising a threaded rod, a pair of door engaging nuts threaded on one end of said rod, a block threaded on the other end of said rod having a flattened face formed on its outer edge, the other portion of the outer edge being provided with a plurality of transversely extending grooves, and a frangible cable secured to said block diametrically opposite the flattened face formed thereon.

3. The combination with a vault door including an outwardly extending flange arranged adjacent to the forward edge of the

- door, of a locking device for the door including a plurality of bolts arranged to be projected through the flange and a bar connecting the bolt, a rod secured to the flange, 5 a combination lock mechanism arranged to prevent movement of the bolt mechanism, and a block rotatably mounted on the rod and arranged at right angles to the bar, the block having a flat face, means for preventing 10 the accidental rotation of the block, and a means secured to the block at an angle to the flat face thereof and passed over the combination mechanism and anchored adjacent thereto.
- 15 4. An attachment for the bolt mechanism of vault doors comprising a rod having its ends threaded, a pair of lock nuts arranged on one threaded end of the rod, a rotatable substantially circular block threadably 20 mounted on the opposite threaded end of the rod, means arranged on the rod adapted to engage the block to prevent accidental rotation thereof, the block having one face thereof flattened.
- 25 5. The combination with a vault door, of a locking device for the door including a bolt mechanism, and a combination mechanism for holding the bolt mechanism in operative position, a rod carried by the door, 30 and a block rotatably mounted on the rod, and means for moving the block into the path of the bolt mechanism for preventing the operation thereof upon the destroying of the combination mechanism, and a pro- 35 tector mounted on said means.
6. The combination with a vault door, of a locking device for the door including a
- bolt mechanism and a combination mechanism for holding the bolt mechanism in operative position, a rod carried by the door, 40 and a block rotatably mounted on the rod, and means for moving the block into the path of the bolt mechanism for preventing the operation thereof upon the destroying 45 of the combination mechanism, and a pro- tector rotatably mounted on said means.
7. The combination with a vault door, of a locking device for the door including a bolt mechanism and a combination mechanism for holding the bolt mechanism in op- 50 erative position, a rod carried by the door, and a block rotatably mounted on the rod, and means for moving the block into the path of the bolt mechanism for preventing the operation thereof upon the destroying 55 of the combination mechanism, and a cylindrical shell rotatably mounted on said means.
8. The combination with a vault door having a flange extending adjacent to the forward edge thereof, of a locking device for 60 the door including a plurality of spaced bolts arranged to be projected through the flange, and a bar connecting the bolts, a rod secured to the door flange, a block rotatably mounted on the rod and having a flat face 65 arranged to normally lie in parallel relation to the bar to permit movement thereof, and a connector secured to the block and having its lower end anchored adjacent to the combination mechanism, and a cylindrical shell 70 rotatably and removably mounted on said connector intermediate the bolt and combination mechanism.

WILLIAM C. DILLON.
